UNITED STATES PATENT OFFICE.

CHARLES W. DAKE AND ROBERT S. LEVIS, OF CHICAGO, ILLINOIS, ASSIGNEES TO THE PYLE-NATIONAL COMPANY, OF CHICAGO, ILLINOIS, A CORPORATION OF NEW JERSEY.

GLASS-POLISHING MACHINE.

Application filed October 2, 1922. Serial No. 591,756.

Our invention relates to improvements in machines for grinding and polishing glass and particularly to a machine for polishing the outside of a glass reflector bowl 5 for locomotive electric headlights and the like.

These bowls are first cast and may be parabolic, spherical, conical or may be made up of a combination of such surfaces. The 10 bowls are ground on the outside to the desired shape but the grinding leaves a certain amount of scratches, tool marks and the like which must be eliminated by polishing before the bowl is ready to be plated to form 15 a reflector and one of the major objects of this invention is to provide a polishing machine and particularly a polishing element which will polish the bowl, remove the tool marks, and will still retain without change 20 the original shape and contour of the outer bowl surface. Another object is to provide a polishing machine which will make use of the polishing element. Other objects will appear from time to time in the specification. 25

Our invention is illustrated more or less diagrammatically in the accompanying drawings wherein

Fig. 1 is a side elevation with parts broken 30 away of the polishing machine,

Fig. 2 is an upper plan view of the supporting and driving mechanism for the polishing pad or member,

Fig. 3 is a section on an enlarged scale 35 through such polishing pad.

Like parts are indicated by like characters in the drawing.

A is a machine bed or base carried on the legs A'. Projecting upwardly from it is the 40 tail bearing bracket A², and intermediate bearing bracket A³, and a head bearing bracket A⁴. The brackets A² and A⁴ are provided with the usual form of bearings A⁵ and A⁶ in which the hollow spindle A⁷ 45 is mounted. This hollow spindle carries a sleeve A⁸ rotatably mounted thereon which carries at one end a miter gear A⁹ in mesh with a miter pinion A¹⁰ on a suitable drive shaft. At the other end of the sleeve is a 50 clutch disc A¹¹ adapted to engage a clutch disc A¹² splined on the shaft A⁷ held in op-

erative engagement with the disc A¹¹ by the spring A¹³ and adapted to be thrown out of engagement by lever A¹⁴ controlled by handle A¹⁵.

B is a chuck plate carried by shaft A⁷. B¹ is the reflector bowl adapted to seat against the face of the chuck plate B and to be held in position thereon by air pressure when the air inside the bowl and between it and the chuck plate is exhausted. B² is a bracket which carries the coupling B³. Leading into this coupling is a pipe B⁴ communicating with any suitable vacuum pump or exhaust. B⁵ is a short pipe leading from the coupling B³ to and communicating with the end of the hollow shaft A⁷ so that air can be exhausted from the interior of the bowl through the shaft, coupling and pipe to the vacuum pump not 70 shown.

There is a worm C keyed to the shaft A⁷ and in mesh with a worm wheel C¹ on the gear shaft C². The gear C³ is in mesh with a pinion C⁴ on the pinion shaft C⁵. C⁶ is 75 a miter pinion on this shaft in mesh with a pinion C⁷ on the inclined shaft C⁸ which shaft terminates in a pulley C⁹.

The polishing pad is made up of the circular cup D having just inside its periphery the outwardly projecting flange D¹ to form a lenticular bowl-like chamber closed on its outer sides by the rubber diaphragm D² and the felt polishing pad D³. This diaphragm and polishing pad pass around the flange D¹ and are tightly clamped against the face of the disc by means of the annular ring member D⁴, which is held tightly against the felt and rubber by means of the bolts D⁵, there being a packing washer D⁶ between the felt and rubber elements beneath the clamping ring so as to make a permanent airtight joint. D⁷ is an ordinary type of automobile tire valve screwed into the boss D⁸ so that the air chamber may be filled 90 with compressed air and the polishing pad inflated to any suitable pressure. The felt element will have on the surface where it engages the bowl B¹ a suitable supply of rouge or other polishing abrasive, and the fact that the working portion of the pad is held against the bowl by air pressure only 95 100

causes the surface of the pad to conform absolutely to the previously arranged contour of the bowl and therefore as the polishing continues no change in shape of the bowl 5 can take place because the pressure of the various portions of the pad where they press upon the bowl is always the same for every unit of area.

E is a stub shaft upon which the member 10 D is mounted. It terminates at the other end in a belt pulley E¹. E² is a hub having an anti-friction lining E³ and surrounding the shaft E. Projecting laterally from this hub are the trunnions E⁴ pivoted in the 15 frame E⁵ so that the shaft E may swing in a plane parallel with the longer axis of the frame E⁵. The frame E⁵ is itself pivoted on the stirrup E⁶ which in turn is mounted on a bracket E⁷ on the supporting 20 frame E⁸, which latter frame is rigidly mounted on base A and also serves as a guide and support for the clutch lever handle A¹⁵. E⁹ is a belt passing over the pulleys C⁹ and E¹ so that when the shaft A⁷ is rotated to 25 rotate the bowl the polishing pad is also rotated in engagement with the bowl, thus bringing various portions of the polishing pad and the bowl into engagement one with the other and insuring the proper operation 30 of the polishing element. E¹⁰ is a lever projecting outwardly from the frame E⁵ so that a weight may be applied to increase the pressure of the polishing element if that is desired.

35 F is a semi-cylindrical shield supported on the bracket arms F¹ from the frame A. It is closed at the ends and encloses the lower half of the bowl and the chuck and comes up above the lower extremity of the 40 polishing pad.

It will be evident that while we have shown in our drawings an operating device still many changes might be made in the size, shape and arrangement of our invention 45 without departing materially from the spirit thereof, and we wish, therefore, that our drawing be regarded in a real sense as diagrammatic.

We have shown the inflatable receptacle 50 adapted to be filled with air. Obviously, it might be inflated with gas, water, or oil or any other suitable fluid or liquid, though for its convenience air is the preferred medium. We have used in the claims "pneumatic." It is to be understood that the 55 term pneumatic in a broad sense is not merely limited to air but directed to filling the receptacle with any liquid under pressure to give the desired equalizing result.

30 The use and operation of our invention are as follows:

The reflector bowls which are first cast, 55 preferably by a process similar to die casting, to give them the approximate size and shape are ground to correct shape on any

suitable grinding machine which forms no part of my present invention. These bowls ordinarily have a central aperture through which the lighting element is introduced into the searchlight. This hole is closed by a 70 suitable removable plug. The open face of the bowl is then brought into engagement with the chuck disc which at that time is at rest, and the air is sucked out from the space between the bowl and the plate to 75 cause the bowl to be held in position by atmospheric pressure. The polisher frame which prior to that time is held away from the bowl is lowered until the pad itself engages the outer surface of the bowl. The driving belt is then put in place and the clutch is thrown to start rotation of the shaft. This rotation of the shaft causes the 80 bowl to spin. It also causes the polishing pad to spin or rotate in engagement with the 85 bowl and this rotation of the bowl and the pad continues until the polishing has been completed.

The use of the air inflated polishing pad 90 makes it possible to have the pressure of the polishing element against the bowl the same at every point. It enables the rather thin, flexible polishing surface to correctly insure that as polishing takes place the shape 95 of the bowl will not change. It also insures that the tool marks left on the bowl by the grinding process will not be expanded or increased as might be the case if a rigidly backed polishing surface were used. 100

We claim:

1. A pad for glass polishing machines and the like comprising a rigid flanged circular plate, a flexible impervious diaphragm closing the bowl formed by the plate and flange a flexible polishing pad supported by the impervious diaphragm, the periphery of the pad and the diaphragm extending beyond and enfolding the flange, an annular ring encircling the outer periphery of the plate and having an inwardly extending flange parallel with the face of the plate, the inner diameter of said flange being greater than the outer diameter of the flange on the plate and means for clamping the flange and the edge of the plate together, said means being located outside the plate flange. 115

2. A pad for glass polishing machines and the like comprising a rigid bowl of generally circular cross section, a flange projecting laterally beyond the mouth of the bowl, the plane of the flange being located below the mouth of the bowl, a flanged annular ring, the inner diameter of the ring being substantially the same as the outer diameter of the flange, the inner diameter of the flanged portion of the ring being greater than the outer diameter of the bowl, a flexible impervious diaphragm closing the bowl, a flexible polishing pad supported by the im- 120

pervious diaphragm, the outer edges of diaphragm and pad extending around the edge of the bowl between the inner edge of the flange on the ring and the outer edge of the bowl and extending laterally between the surface of the bowl flange and the surface of the ring flange and means for drawing the two flanges together and to clamp the pad and the diaphragm on the bowl and

provide a gas tight chamber formed by the 10 bowl and the diaphragm.

Signed at Chicago, Illinois, this 23rd day of September, 1922.
